I. Ambler, Jr.

Portable Soda Fountain.

Patented June 13, 1831.

(Date 18. 1. 53)

242.

P. John Amble for Channing A. U.

Sexton's Patent

The Schedule referred to in these Sexton's Patent and making part of the same containing a description in the words of the said John Amble from himself of his improvement in the apparatus for making Soda Water.

Be it known that I John Amble have invented an apparatus for making Soda Water by mixing two separate solutions in the art of drawing off the liquids and that to following is a full and exact description of the same.

I make a Cistern or reservoir which divide into two parts by a partition across the same so I make two reservoirs and place them together so that they shall answer the same purpose. Into one of the compartments is put a solution of tartaric acid or any other suitable acid and into the other a solution of the super-o-hydro-carbonate of Soda usually in the proportion of about five parts of the former to one of the latter. When the solutions are so mixed in the art of drawing, which produces an active effervescence in the receiving vessel to draw off these liquids I make a stop cock in the shank of which there are two ports one above the other a tube from one is connected with the acid and the other with the saline solution. The opening in the key of the cock is made strong so as to allow the liquids to combine in it & flowing together through the stop cock. I sometimes substitute the valves closing the openings in the cistern than the openings are to be connected by tubes uniting together & having an adjustable stopper to both, the stems of these tubes are to be so constructed that by sliding, pressing or turning a button or other contrivance they shall act simultaneously.

What I claim as my invention and for which I ask a Patent is the improvement of a stop cock with the openings in the shank of said part so as to act as above described with also the substitution of valves operated upon by a single movement in any of the ways familiar to mechanical art.

Witnessed at Boston
John Amble
